TOILET ARTICLE

Irving Wexler, New York, N. Y., assignor to The
R. H. Laird Manufacturing Company, Inc.,
New York, N. Y., a corporation of New York

Application July 9, 1942, Serial No. 450,351

9 Claims. (Cl. 33—18)

This invention is a marking device for producing a mark on the leg simulating the seam of a stocking.

The custom of going without stockings seems to be on the increase among women, especially with the advent of warm weather, and also because of the shortage of materials for making stockings. In order to overcome the bare-legged appearance, women are using what might be called "cosmetic hosiery," where the leg is coated with a paste or lotion of the shade of a stocking. Since, however, women's stockings are provided with a seam, it becomes necessary with such cosmetic hosiery to provide a mark simulating such seam, to give a good simulation of actual hosiery.

It is difficult for women to produce a seam-simulating mark with a crayon, especially since the seam is on the back of the leg. The principal object of the invention is to produce a marker whereby a woman can quickly and accurately produce a mark which is approximately straight and as long as may be desired.

An important feature of the invention is that the marker acts as a guide for properly engaging the ankle, calf and thigh portions of the leg, as the case may be, of a particular user. It is also capable of use with various sized legs.

More particularly, the marker is approximately Y-shaped, comprising diverging arms for engaging part-way around the leg, in combination with a crayon or marker positioned between these arms for producing a line on the leg simulating the stocking seam.

The stem of the Y-shaped member acts as a manipulating handle and the marking crayon is carried by this handle portion, the crayon preferably fitting in a hole through the handle with a sliding friction fit, so that it may be positioned in exactly the right place.

Another important feature of the invention is that the inner edges of the arms of the Y-member are preferably formed with a succession of curved depressions which define ridges between such depressions. The depressions or ridges, or both, engage with the leg and act as guides for aiding in keeping the marker moving in a substantially straight line.

The marker may be made of any suitable material, such as wood, plastic, rubber or metal, if such latter materials are available. If rubber is available, the arms may be made of fairly soft rubber so as to be somewhat elastic for snugly engaging any part of the leg of the wearer with which it may be used.

The invention will be further described in connection with the accompanying drawing, in which:

Fig. 1 is a perspective view of the marker in accordance with the present invention.

Fig. 2 is a plan view of the same; and

Fig. 3 is a sectional view on the line 3—3 of Fig. 2.

In the drawing, the marker comprises diverging arms 2 joined to a common base or handle member 4, which may be provided with a groove 6 on one or both sides for the thumb or fingers. The stem or handle 4 carries a marker 8 which conveniently may be in the form of a crayon or eye-brow pencil in any suitable color, passing through a hole 10 in the handle 4. The marker 8 fits fairly snugly in the hole 10 so as to be slideable back and forth therein with a friction fit, so that it will remain in any desired adjusted position. The marker 8 is readily removable, in case a seam of another color is desired. If loose, a layer or two of paper will make it sufficiently tight. Or, if desired, a small leaf spring 12 may be positioned in the hole 10 for pressing against the marker to provide a friction fit and the marker may, if desired, be provided with concavities or depressions 14 into which the spring 12 fits, for holding the marker in adjusted position.

The arms 2 are preferably provided along their inner edges with a series of curved depressions 16, 18 and 20, which define between them ridges 22 and 24. The arms 2 could be straight or otherwise curved, as desired.

In use, with the crayon 8 in proper position, the marker is placed over the heel of the wearer with the crayon in contact with the back of the heel and with the marker slanting diagonally upwardly. In this position the ridges 22, and perhaps parts of surfaces 16 will be in contact with the heel. The marker is then drawn upwardly, being gradually brought toward the horizontal position; after travelling past the calf of the leg would probably be slanted somewhat downwardly. However, in whatever position it

may be, some portions of the depressions 16, 18 or 20 or some of the ridges 22 and 24, or both, would be in contact with the leg and would act as guides for keeping the marker moving and in contact with the leg, so as to produce a substantially straight line, in the desired position on the leg, to simulate a stocking seam with accuracy.

While the invention has been illustrated in some detail, it should be understood that it is not to be limited to the exact details as shown, but may be carried out in other ways.

I claim as my invention:

1. A toilet article for use in producing a mark simulating the seam of a stocking, comprising a substantially Y-shaped guide, a marker positioned at the apex of said guide and frictionally held and slidably adjustable therein.

2. A toilet article for use in simulating the seam of a stocking, comprising a substantially Y-shaped guide, the arms of said guide being of varied contour on their inner edges for accommodating legs of various sizes, a marker positioned at the apex of the guide and slidably adjustable therein, for producing a simulated seam as the guide is moved along the leg.

3. A toilet article for producing a mark on the leg, simulating the seam of a stocking, comprising a substantially Y-shaped member, the inner edges of said arms being formed in a succession of curved depressions, defining ridges between them, and a marker positioned between said arms.

4. A toilet article for producing a mark on the leg, simulating the seam of a stocking, comprising a substantially Y-shaped member, for accommodating different portions of the leg, the stem of said Y-shaped member providing an operating handle, and a marker carried by said handle and projecting between the arms of the Y-member.

5. A toilet article for producing a mark on the leg, simulating the seam of a stocking, comprising a substantially Y-shaped member, for accommodating different portions of the leg, the stem of said Y-shaped member being grooved to serve as an operating handle, and a marker passing through said handle with a friction fit and projecting between the arms of the Y-member.

6. A toilet article for use in simulating a seam of a stocking, comprising a body portion forming an operating handle, diverging arms extending from one end of said handle adapted to slidably engage the leg of the user, a marker supported by said handle to operatively engage the rear of the leg for drawing a line thereon, as said arms are moved along in contact with the leg.

7. A toilet article for use in simulating a seam of a stocking, comprising a body portion forming an operating handle, diverging arms extending from one end of said handle adapted to slidably engage the leg of the user, a variably positionable marker carried by said handle for engaging the rear of the leg of the user for drawing a line thereon as said arms are moved along in contact with the sides of the leg.

8. A toilet article as in claim 6, wherein said diverging arms are made of flexible material.

9. A toilet article as in claim 7, wherein said diverging arms are made of flexible material.

IRVING WEXLER.
